DESIGN FOR A BRACELET OR SIMILAR ARTICLE

Jerry Rappaport, New York, N. Y., assignor to Du Barry Novelty Co., New York, N. Y., a co-partnership consisting of Alexander Greene and Jerry Rappaport

Application December 20, 1939, Serial No. 89,037

Term of patent 7 years

To all whom it may concern:

Be it known that I, Jerry Rappaport, a citizen of the United States, residing in the Borough of Manhattan, city, county, and State of New York, have invented a new, original, and ornamental Design for a Bracelet or Similar Article, of which the following is a specification, reference being had to the accompanying drawing, forming a part thereof, in which:

Fig. 1 is a front elevation of a bracelet or similar article embodying my new design;

Fig. 2 is similar to Fig. 1 but shows the spherical members removed and alternate supporting means are shown as broken away;

Fig. 3 is an end elevation of one of the spherical members showing the support therefor.

I claim:

The ornamental design for a bracelet or similar article, as shown.

JERRY RAPPAPORT.
